ALFRED FRANCIS.

UNITED STATES PATENT OFFICE.

JOHN QUINCY REED, OF NEW YORK, N. Y., ASSIGNOR TO THE BUTTERICK PUBLISHING CO., (LIMITED,) OF SAME PLACE.

DESIGN FOR A LADY'S DRESS-BASQUE.

SPECIFICATION forming part of Design No. 14,371, dated October 23, 1883.

Application filed August 23, 1883. Term of patent 3½ years.

To all whom it may concern:

Be it known that I, JOHN QUINCY REED, of the city, county, and State of New York, have invented and produced a new and original Design for a Pattern of a Lady's Dress-Basque, (numbered 8,817;) and I do hereby declare that the engraved prints accompanying this specification convey to any one accustomed to using paper patterns a clear understanding of how a garment made up by the pattern will appear.

The design combines a closely-fitted pointed front, a closely-fitted pointed back buttoned down the center, and a graduated plaiting that makes the lower edge of uniform depth

all around. Coat-sleeves and a standing collar are added, as shown in the back view; but the sleeves may be shortened and the neck cut in Pompadour shape, as shown in the front view.

What I claim as my invention, and desire to secure by Letters Patent, is—

The design for a lady's dress-basque, as shown in the engraved prints accompanying this specification.

JOHN QUINCY REED.
